PROCESS OF PERMANENTLY WAVING HAIR AND APPARATUS THEREFOR

Filed Feb. 24, 1930

UNITED STATES PATENT OFFICE

RAYMOND CASTELLA AND JEAN NANTUA, OF LAUSANNE, SWITZERLAND

PROCESS OF PERMANENTLY WAVING HAIR AND APPARATUS THEREFOR

Application filed February 24, 1930, Serial No. 430,776, and in Switzerland April 9, 1929.

This invention relates to an improved process of permanently waving hair and apparatus therefor.

In permanent hair-waving processes which cause a modification of structure of the hair, particularly ceratinization, the essential features are the degree of temperature and the duration of applied heat. Excessive heat is liable to burn and destroy the hair, whilst heating at a temperature insufficiently high must, in order to attain the desired result, be prolonged too much; this is liable to evaporate the liquid under the influence of which the ceratine is to be modified and consequently to dry the hair which swells, bursts and loses its suppleness.

The process according to the present invention has for its object to limit to a strict minimum the duration of the heating, to reduce as much as possible the quantity of liquid to be evaporated in order to effect the modification of the ceratin and thus to bring about in a very short space of time the transformation of straight into wavy hair.

The apparatus according to the invention for carrying this process into practice comprises (a) moistening devices each composed of a thin sheet of metal and a layer of fibrous material, which moisteners are intended to be detachably placed on the various tresses or locks of hair wound on the usual mandrels, and (b) a heating device mounted on a sleeve and intended to be placed successively and for a predetermined time on each moistener.

One form of apparatus according to the invention is diagrammatically illustrated by way of example in the accompanying drawing, wherein:

Figure 1 shows in section and in elevation several moisteners arranged on the mandrels each carrying a lock of hair,

Figure 2 is an elevation, partly in vertical section, showing an electric heating device,

Figure 2a shows a modification of the means for securing a timing element to the heater handle,

Figure 3 shows on an enlarged scale a longitudinal section of a moistener provided with a protector,

Figure 3a is a fragmentary sectional view

on an enlarged scale showing the relative arrangement of the linings forming the moistener,

Figure 4 is bottom plan view of the protector, and

Figure 5 shows another form of protector. Like reference characters designate like parts throughout the several views.

Each tress or lock 1 of hair is wound on a mandrel 2 of the usual kind having its lower end in a protector 3. These protectors comprise each a disk 13 of yielding or supple material, preferably india rubber. Each disc 13 has a conical flange 14 surrounding a metallic body 15, e. g., of aluminium, having one portion conical and another portion cylindrical. The cylindrical portion of each body 15 extends beyond the flange 14. A circular hole 16 is made eccentrically in the disc 13, and around it radial notches 17 are cut symmetrically. Below the disc 13 is placed a second disc 18 having a central hole 19 and radial notches 20. The lock 1 of hair to be waved is threaded first through the hole 19

of the disc 18 which consequently bears directly against the scalp, and then through the hole 16 in the disc 13. These two holes are then moved out of register, whereby the vapor arising from the heated impregnated lock 1 is prevented from passing through the holes 16 and 19 and burning the head of the person under treatment. The radial notches 17 and 20 form elastic points which compress the base of the lock 1 and enhance the fluid tightness of the protector.

A conical moistener 4 is threaded on each lock which is impregnated in the usual manner with a liquid serving to modify the ceratin. Each moistener 4 comprises a thin metallic sheet forming its external face, and a layer of fibrous material, vegetable or mineral, forming its internal face. This layer of fibrous material may be impregnated with any suitable chemical material.

The electric heater shown in Figure 2 comprises two tubular members 5 and 6, whereof one (5) open at its ends is surrounded by the other (6). The tube 5 whose internal diameter is preferably not less than 13 mm. and not more than 16 mm. is longer

than the tube 6 and extends at both ends beyond the later. The end 7 of the tube 5 intended to be introduced during the heating operation into the protector 3 of each lock, 5 is slightly splayed in the form of a cone so as to fit the shape of the lock of hair whereof the diameter is greater at the roots.

It is to be noted that the length of the end portion 7 of the tube 5 is less than the height 10 of the protector 3 so that during the heating operation the said end portion cannot come into contact with the bottom of a protector and the lock of hair traversing it.

Between the two members 5 and 6 is placed 15 a resistance or heating element 8. This resistance of coiled wire is wound around the tube 5 suitably insulated. Preferably the coils of the resistance are closer together towards the end 7 of the tube 5 in order to provide greater heat towards the base of the lock 1 and near its roots.

A hollow handle member 9 through which pass conductors 10 for an electric current is fixed at right angles to the member 6. This 25 handle terminates in a grip 11 of wood or convenient material that does not conduct heat or electricity. On this grip 11 is fixed a timepiece 12, e. g. a stop watch, permitting seconds of time of heating each lock of hair 30 to be read on it. In the example illustrated the watch or chronometer 12 is mounted above the grip 11, but if desired it may be fixed horizontally on a ring 12a rotatably carried by the grip 11 as shown in Fig. 2a.

35 In this case the crown of the watch is turned to contact directly with the thumb of the operator's hand and the dial lies at 180° to the crown so that its figures face the operator's eyes who is thus able to perform with only 40 one hand all the movements of the device necessary for the heating operation. Also, the timepiece may be constructed as or combined with a circuit breaker in such manner as to close the circuit of the resistance 8 when it 45 is started and to open it when it stops.

Instead of being heated electrically the 50 heater may be heated in any other manner. In this case, the body 5, 6 is preferably a solid body pierced with a conical duct whereof the conicity corresponds to that of the moistener. This body may be heated, for example, on a 55 gas burner, a spirit burner or in a suitable furnace or in any other convenient manner.

60 In order to heat the locks of hair the heating device heated beforehand to the desired temperature is applied successively to all the moisteners 4, as indicated in broken lines in Fig. 1. The heater remains on each of these 65 for a predetermined period, e. g. 30 or 40 seconds, controlled by means of the timepiece. The rapid heating having been effected, the moisteners remain in situ until the mandrels 2 have cooled. Each moistener 70 is then removed by a single movement, it

being withdrawn by lifting away the allotted protector.

In this manner not only is the liquid modifier, with which the locks are impregnated, rapidly boiled, but after the heater is removed the escape of the vapors generated is prevented and the lock of hair is not immediately cooled. Moreover, the improved process and apparatus described above permit a more rapid and acute action of the heat to the base of the hair than do processes and apparatus proposed heretofore.

The metallic sheath of each moistener as shown in Fig. 3a is composed e. g. of 15 aluminium or aluminium paper, whilst the layer of fibrous material may be composed of asbestos, asbestos paper or like refractory material. Each moistener may be made by rolling conically on itself a sheet or band formed of the two layers affixed one to the other, e. g. by an adhesive, thus making a 20 spiral structure, and closing the cone thus obtained by pinching its pointed end. Alternatively, the said sheet or band may be 25 rolled up on itself conically or cylindrically 30 and be held in that form by an external ring.

Furthermore, the metallic sheet may be 35 coated with a suitable paint adapted to change its color under the action of the heat of the heating device to indicate the progress 40 of the operation. For the same purpose the metallic sheath of each moistener may carry a movable index for marking the passage of the heater over it or, alternatively, it may 45 carry any mark which the heat of the heater 50 causes to appear or disappear.

These and various other modifications may 55 be made in the details of construction set forth above without departing from the invention as defined by the claims.

We claim:—

1. In hair-waving apparatus, the combination of a cup-shaped protector comprising at least one disk of yielding material having a hole with radial notches radiating therefrom for the passage of the hair, and a tubular moistener extending into said protector, and forming an annular space between said moistener and protector for the introduction of a heating element.

2. In hair-waving apparatus, the combination of a protector in the form of a socket having at its closed end two disks of yielding material superposed one on the other and having each a hole for the passage of hair, the hole in one disk being out of register with the hole in the other disk, and a tubular moistener extending into said protector, and forming an annular space between said moistener and protector for the introduction of a heating element.

3. In hair-waving apparatus, the combination of a protector comprising a disk of yielding material having a conical flange and a hole for the passage of hair, and a metal

ring surrounded by said flange, and a tubular moistener extending into said ring, and forming an annular space between the moistener and ring for the introduction of a heating element, said moistener receiving a mandrel on which hair to be treated is wound.

4. In hair-waving apparatus, the combination of a protector comprising two disks of yielding material superposed one on the other and having each a hole for the passage of hair, the hole in one disk being out of register with the hole in the other, and each hole having notches radiating symmetrically therefrom, one of which disks has an upwardly standing conical flange, a metal ring having a conical portion surrounded by said flange and a cylindrical portion extending beyond the latter, a tubular moistener extending into said ring and bearing on said flanged disk, and forming an annular space between the moistener and ring for the introduction of a heating element, and a mandrel on which hair is to be wound in said moistener.

5. As an article of manufacture, a protector and a tubular moistener comprising a thin metal sheath extending into said protector, which sheath has internally adhering to it a lining of fibrous refractory material.

In testimony whereof we affix our signatures.
